INDICATOR OF DETONATIONS FOR INTERNAL COMBUSTION ENGINES

Max Yves Antonin Serruys, Paris, France

Application December 17, 1934, Serial No. 757,873
In France December 21, 1933

1 Claim. (Cl. 177—311)

Apparatus for measuring the value of the impact due to the detonating action of internal combustion engines are in use at the present time, and in particular the apparatus termed 5 "Bouncing pin", which is mounted by the General Motors Company upon certain engines used for testing. Such apparatus are characterized by the use of a small chamber or thin flat metallic diaphragm subjected to the pressure, a 10 vibrating rod in contact with the said diaphragm, an electric contact device actuated by the said rod, and an electric apparatus for measuring the mean current passing through the said contact device.

15 Other detonation responsive devices are known, which include a diaphragm responsive to engine pressure, contact means including a contact carried by the diaphragm and a second contact, and indicating means responsive to separation or to 20 mutual engagement of said contacts.

All the aforesaid apparatus are responsive to the pressure which prevails in the explosion chamber of the cylinder under test.

The primary object of my invention is to provide 25 a detonation responsive device which will be irresponsible to the pressure in the explosion chamber.

With this aim in view, I make use as a detonation responsive device of a device responsive to 30 pressure-acceleration including a diaphragm responsive to engine pressure and contact means including a contact carried by the diaphragm, and in which resilient means normally hold a second contact in engagement with the first 35 named contact, the force exerted by the resilient means and the mass of the second contact being such that under normal operation the second contact will follow and remain in contact with the first, but under a detonation the second contact 40 will separate from the first, and indicating means responsive to the opening of the contacts.

The accompanying drawing shows by way of example an embodiment of the invention.

As shown in the drawing, the detonation indicator, which is secured to the cylinder head 1 and is connected with the explosion chamber 2, 45 comprises a small block 3 secured to a diaphragm 4, which is mounted, by a non-leaking joint, in the main body 5 of the indicator, and whose lower side 6 is connected, by a conduit 7, with the explosion chamber 2. As shown in the drawing, the conduit 7 has practically the form of a venturi, thus affording the most approved transmission of the instantaneous pressure to the diaphragm 4. A movable block 8 is placed in direct contact, in the idle position, with the block 3 by a spring 9. The block 8 is guided by an insulating disc 10, and the diaphragm 4, the disc 10 and a packing ring 11 are held in position by a 50 plug 12. The block 8 is electrically connected

through the spring 9 and a metallic rod 13, insulated at 14, with an induction coil 15, whose primary is supplied by a source of current 17 whose other end is connected to earth by the metal parts, as well as the cylinder head 1. The 5 secondary 18 of the coil is connected with a neon tube 19. The diaphragm, the blocks 3 and 8, and the spring 9 are so designed that during the normal working of the engine, the spring 9 will constantly hold the block 8 against the block 3 10 but when the explosion in the chamber 2 has the character of a detonation, the block 3 will be imparted an acceleration greater than that imparted to the block 8 by the spring 9, so that the block 3 will separate from the block 8 during 15 the return stroke of the diaphragm to its rest position, thus breaking the primary circuit 16 and producing an induced high-tension current in the secondary 18, hence lighting the neon tube 19.

It is important to note the following:

1. The block 8 is in direct contact with the block 3, without the interposition of any vibrating rod, which affords a very small and light device.

2. The spring 9 can be easily adjusted in such 25 way that the non-detonating explosions can never separate the contact blocks 3 and 8, but that any slight detonations will break this contact.

3. The neon tube may be permanently mounted 30 on the front board or on the control board of an aeroplane or automobile, or testing bench containing the engine under test, or upon a moving part of said engine, and the position of this part, at the time when the tube lights up, will 35 show the point of the cycle at which the detonation takes place; such an arrangement of the invention can be made by any person skilled in the art, and need not be further described.

4. The apparatus can be used not only as an 40 apparatus for observation or control, but as a safety device, and especially upon an aeroplane, in order to attract the attention of the pilot each time that an improper maneuver or a defective operating of the engine causes it to detonate.

45 What I claim is:

In a detonation responsive device for internal combustion engines means including a diaphragm 50 responsive to engine pressure and contact means including a contact carried by the diaphragm, a second contact, resilient means for normally holding the latter in engagement with the first-named contact, the force exerted by the resilient means and the mass of the second-contact being such 55 that under normal operation the second contact will follow and remain in contact with the first, but under a detonation the second contact will separate from the first, and indicating means responsive to the opening of the contacts.
